PLATE HEAT EXCHANGER

Robert P. Larsson Hytte, Lund, Sweden, assignor
to Aktiebolaget Separator, Stockholm, Sweden,
a corporation of Sweden

Application August 29, 1947, Serial No. 771,399
In Sweden February 10, 1942

Section 1, Public Law 690, August 3, 1946
Patent expires February 10, 1962

5 Claims. (Cl. 257—245)

1

Heat exchangers of the plate type comprise a number of juxtaposed plates, between which tight joints are established by means of packings located at the rim of the plates. Between the plates thus spaced apart by the packings are formed chambers for the fluids between which heat is to be exchanged. Communication between the interspaces on the one side and the supply and discharge channels on the other side of the plates is obtained by means of openings in the plates located in front of each other. The fluid traversing the interspace enters through one of the openings and discharges through another opening. Since there are two fluids between which heat is to be exchanged, two pairs of openings must be provided in the plates, that is one pair for each fluid. Heretofore the discharge opening was positioned diametrically opposite to the supply opening with a view to obtaining as even a distribution as possible of the liquid flow over the heat transmitting surface. The rate of flow should, if possible, be the same over the whole surface. The said relative positions of the supply and discharge openings resulted in the openings for a given interspace being positioned on either side of the apparatus. If the plates are of substantially rectangular shape and are provided with an opening in each corner, this means that the inlet and outlet openings of a given interspace are not positioned consecutively reckoned along the rim of the plate, but they alternate with the openings of the adjacent layers. If we start with the inlet opening of an interspace and go along the rim of the plate, we then come to an opening to the next interspace, and then to the discharge opening from the first interspace, and finally to another opening to the next interspace. The inlet and outlet openings are thus positioned on different sides of the plate, which involves inconveniences with respect to the location of the pipe lines coupled to the apparatus, because it is desirable that the inlet and outlet pipes for a given medium should be coupled to one and the same side of the apparatus.

The alternate location of the inlet and outlet openings of the various interspaces entails the inconvenience that two differently shaped plates must be used alternately. As the packings should be fixed to one of the plates for practical reasons and are therefore placed in packing grooves, all the grooves must open into the same direction if all the plates are to be provided with packings, which is generally the case.

Owing to the dissimilarity of the plates, two

2

complete sets of pressing tools must be used, which entails very considerable costs for the tools because pressing tools of the kind under consideration are very expensive.

According to the invention it becomes possible to use a single type of plate in the apparatus by consecutively locating the inlet and outlet openings of the channel formed by the packings and heat transmitting surfaces of the plates, that is so that the sequence between the openings along the rim of the plate is not interrupted by an opening of the channel in the adjacent interspace. With this arrangement it becomes possible to obtain the desired communications by allowing every second plate to revolve 180° around an axis at right angles to the plane of the plate. The inlet and outlet of the channel in the turned plate are thus positioned adjacent the side which is opposite to that adjacent the inlet and outlet of the non-turned plate. Both plates, the turned and the non-turned one, may be quite alike, and therefore the same tools may be used for the manufacture. The inlets and outlets of a given fluid will thus lie on one and the same side of the apparatus, and the inlets and outlets of the other fluid on the other side.

The accompanying drawings show by way of example one embodiment of the invention. Fig. 1 is a perspective view, somewhat diagrammatical, of a part of an exchanger made according to the invention. Fig. 2 is a top view of the construction illustrated in Fig. 1. Figs. 3 through 8 are sectional views of various shapes of plates; Fig. 9 is a face view of a modified form of the arrangement illustrated in Fig. 2; Fig. 10 is a sectional view across the undulations of two juxtaposed plates; Fig. 11 is a sectional view along the plates; Fig. 12 is a sectional view of modified plates, and Fig. 13 is a plan view of parts of the lower plate of Fig. 12.

As will be seen from Fig. 2, which represents an embodiment of the invention, a circulation pipe 8 of a simple shape may be used. This is accomplished by providing the inlet opening 2 and the outlet opening 3 consecutively at the same side of the apparatus. By placing the inlet and outlet openings in this way it becomes possible, as already mentioned, to establish the required communications also in case only one type of plate is used and every second plate is turned 180° around an axis at right angles to the plane of the plate. As shown in Fig. 2, the plate 12 is so shaped that the channel 14 formed by the plate and the packing 13 is provided with

55

inlet and outlet openings 2 and 3 positioned in uninterrupted succession.

In order to insure uniform distribution of flow across the width of the channel 14 a distributing device must be provided behind the inlet opening 2 and a corresponding equalization device in front of the outlet opening 3. According to the invention the distributing device comprises a rib 15, running right across the channel.

The construction and effect of the distributing rib 15 is illustrated in Fig. 3, which shows the plate 12 in which the rib is pressed, and an adjacent plate 16 forming the opposite wall of the channel 14. Together with the plate 16 the said rib 15 forms a throttled slit 17. The rib 15 is advantageously of different height at the two ends, so that at the one end 18 in front of the inlet opening 2 the width of the slit 17 is less than at the opposite end 19. It will be understood that the width of the slit at different parts of the rib may be so determined that the greater resistance to the flow in front of the opening 2 compensates that otherwise greater resistance to which the liquid flowing past 19 is exposed, or in other words a uniform flow across the width of the plate may be established. In the neighborhood of the opening 3 is a rib 20 which cooperates with the plate 16 for the formation of a slit. This slit, too, should advantageously be narrower at 18 than at 19. The rib 20 may sometimes be omitted.

That part of the interspace or the channel 14 which is positioned between the ribs 15 and 20 should be provided, at suitable places, with pressed-up distance lugs or ribs 21, which contact with the plate 16. Contact lugs in the slit 17 should be avoided, because such lugs together with the high rate of flow would cause liquid-free spaces behind the lugs.

Fig. 4 shows another embodiment of the distributing device, according to which both plates 12 and 16 are provided with rib-shaped portions 150 and the slit, or throttled passage between them, 170, is formed by their lateral walls.

Fig. 5 illustrates a modification of the embodiment according to Fig. 4. The rib 151, functioning like the rib 15 of Fig. 3, is in this case of V shape and provided with sloping lateral walls, and a corresponding pressed portion 22 is provided in the plate 16. Between the sloping walls the slit 171 is formed. When the plate 16 is turned 180° relative to the plate 12 in the manner indicated, the slit 171 is still obtained in its unchanged form. As the width of the slit 171 should increase from the one end of the rib to the other, the ribs 151 and 22 should form a small angle.

Fig. 6 shows the embodiment of Fig. 5 but provided with supporting lugs 25 and 26. However, as the lug 25 is located in the slit or throttle passage 172 it may be omitted and only the lug 26 provided.

Sometimes it is desirable that the heat transmitting surface should be plaited or corrugated steplike, that is so that the channel formed between two adjacent plates becomes zigzag-shaped. The plait or corrugations will then extend right across the plate and will have the character of ribs pressed in the sheet. They will be parallel with the distributing ribs 15 and 20. All the ribs may have the same contour. One such embodiment of the distributing ribs is shown in Fig. 7, where 28 and 29 are the plates having the described zig-zag shape. In Fig. 8 I have shown a sectional view of one of the pairs of

plates forming between them a slit 173 corresponding to the slit 17 of Fig. 3, the width of which is reduced towards one end.

I have illustrated in Fig. 9 a modification of the plate shown in Fig. 2. The plate, instead of having a rectangular shape, has the shape of a parallelogram with sloping sides. Whereas according to Fig. 2 one plate is a reflected image of the other plate, the symmetry between the upper plate and the plate below it of Fig. 9 is of another character. It is, however, possible, in the construction of Fig. 9 as well as in the construction of Fig. 2, to obtain the desired paths of flow by turning every second plate of the set 180° around an axis at right angles to the plane of the plate. As may be seen more clearly from Fig. 9 than from Fig. 2, the openings 60 and 70 are each enclosed by a packing which separates the portion around the opening from the space 140 on one side of the plate 120, whereas the openings 20 and 30 communicate with the said space. The openings 60 and 70 should not communicate with said space but with the corresponding space on the opposite side of the plate 120.

Referring to Fig. 1, which is a perspective view of part of a heat exchanger showing an assembly of three plates, the plates are cut away parallel to one edge of the exchanger and at such distance therefrom as to intersect two series openings (say 2 and 3).

In plate heat exchangers it is generally necessary to take measures in order to insure that the plates are kept in the right position relative to each other. The distance between the plates should be accurately fixed, since the fluid layer should be of a predetermined thickness. The plates, therefore, generally are held in fixed relative positions by distance pieces, usually in the form of lugs or ribs on the surfaces of the plates. If the plates are made of thin pressed sheet steel, the distance pieces are generally pressed in the material in the form of lugs. In the cleaning of the plates it has, however, been found difficult to reach the cavities formed on the rear side of the lugs, because a brush does not penetrate thereto. With a view to facilitating the cleaning of the cavities, the lugs have been made oblong, but this measure, too, has proved unsatisfactory.

The invention relates to the distance pieces of particularly such plates, the heat transmitting surface of which is stepwise undulated or corrugated. With plates of this type the distance lugs were heretofore placed on plane surfaces between the undulations or on the sloping surfaces of the undulations. In both cases the cavity formed on the rear side of the lug has proved to be accessible only with difficulty for brushing and other mechanical cleaning. According to the invention the distance pieces are formed by pressing areas of the bottom of the undulation, not to the full depth of the undulation, but only to a depth which corresponds to the position of the bottom of the undulation of the adjacent plate. The said areas will thus form a support for the adjacent plate. In the latter plate are again corresponding areas which, however, are displaced so much in the direction of the undulations that they contact with the bottoms of the undulations of the next plate. The distance pieces of the following plate may be positioned right over those of the first plate. The distance pieces are thus alternately displaced, that is in

one interspace they are positioned at a given place and in the next at another place.

The undulated plates 101 and 102 are of substantially similar shape and form a zigzag-shaped channel for one of the fluids between which heat is to be exchanged. That portion of the plate 102 which lies in the plane of the sectional view is provided, in the bottom of the undulations, with higher areas 103 which contact with the undulations of the plate 101 and thus support it. The higher areas 103 on the bottom 104 of the plate 102 may be looked upon as pressed-up lugs in the bottom, which however entails that in front of the supporting lug the undulation has a smaller depth than at other places, or in other words the undulation is flattened off at the place of the supporting lug.

In Fig. 11, I have shown a sectional view along the undulations in front of the supporting lug. The bottom 104 of the undulation in the plate 102 slowly rises towards the bottom of the undulation in plate 101 and forms an area or lug 103 which contacts with the bottom of the undulation in plate 101. The plate 102 is provided with a greater or lesser number of such supporting pieces. The plate 101 is in turn provided with a number of similar pressed-up portions 105, which are not positioned in the plane of the section according to Fig. 10 but some distance therewith. The supports 105 may contact with the bottoms of the undulations of a plate not represented on the drawing which is provided with pressed-up areas in front of the areas 103. The higher area 103 forms a depression 106 in the bottom 104. By locating the depressions of the adjacent undulations in line with each other, the surfaces of the depressions become accessible with a brush which is moved along the depressions across the undulations. The direction of movement of the brush is then in the plane of the section according to Fig. 10 and at right angles to the plane of the section of Fig. 11. It will be clearly understood from Fig. 10 that the brush may freely be moved through the depressions 106, so that the surfaces at 103 are efficiently cleaned.

The depressions cause a reduction of the resistance to the flow owing to the increase of the sectional area of the channels resulting from the depressions in the zigzag channel below. Due to this circumstance a number of paths are formed at the depressions having a smaller resistance of flow than at other places of the undulations. These paths with reduced resistance cause so-called accelerated flow, which implies that those parts of the liquid which happen to move along this path reach the outlet of the zigzag channel quicker than the other parts of the liquid. This in turn results in some parts of the liquid not getting the same high temperature as the bulk of the fluid. Such accelerated flow is therefore a very serious inconvenience. It is true that a too quick flow may be avoided by reducing the average speed of the fluid, but this entails considerable disadvantages in two respects. Partly, the capacity of the heat exchanger is reduced, and partly, in some cases, the main portion of the fluid is heated or cooled more than is intended and advantageous.

I have shown in Fig. 12 how the accelerated flow caused by the impressions may be avoided. Below the plate 102 is a plate 107 forming the lower wall of the zigzag channel. The sectional area of the channel in front of the depression 106 is larger than at other parts of the channel.

In order to compensate for this increase of the area the top 108 of the undulation in the plate 101 is so widened that a throttling of the zigzag channel results at 110. The widened portion 111 forms a plane surface of the shape shown in Fig. 13. Since the depressions 106 lie in line with each other, the depressions 111 will also form lines.

In Figs. 10 and 12 all the undulations are provided with supporting members or widened portions 111, but it will be understood that only some of the undulations, for instance every second or third, may be provided therewith.

The subject of this application is disclosed in my application Serial No. 475,240, filed February 9, 1943, now abandoned.

I claim:

1. In a heat exchanger comprising a plurality of plates of like contour, each having a face forming with the faces of the adjacent plates, a pair of separate flow channels, each plate being identical to the others and having four fluid flow openings therethrough near its four corners, packing so arranged on plates carrying the same that when the plates are assembled communication is afforded, through each chamber formed by two adjacent plates, and between pairs of openings along the same edge of the exchanger, said plates being so assembled that the two pairs of communicating openings in adjacent chambers are along opposite edges of the exchanger, and a distributing device extending laterally within each chamber providing a passage progressively widening from the edge of the chamber to which said openings are adjacent toward the opposite edge to thereby effect a substantially equal distribution of the fluid in the part of the chamber beyond the distributing device.

2. In a heat exchanger comprising a plurality of plates of like contour, each having a face forming with the faces of the adjacent plates, a pair of separate flow channels, each plate being identical to the others and having four fluid flow openings therethrough near its four corners, packing so arranged on plates carrying the same that when the plates are assembled communication is afforded, through each chamber formed by two adjacent plates, and between pairs of openings along the same edge of the exchanger, said plates being so assembled that the two pairs of communicating openings in adjacent chambers are along opposite edges of the exchanger, and ridges extending laterally within each chamber near opposite ends thereof adapted to throttle the flow of fluid from the fluid inlet opening to the main body of the chamber and from the main body of the chamber to the fluid outlet opening, each ridge defining a passage gradually widening toward the edge of the plate remote from said last openings.

3. A heat exchanger comprising a series of superposed plates of like contour, namely substantially that of a parallelogram; the plates having like openings having like locations therein, namely, near each of the four corners of each plate; each plate being a duplicate of the others, a gasket applied to one face of each plate, said gasket defining a fluid chamber covering the major area of the plate and enclosing the two openings near the same longitudinal edge of the plate at opposite ends thereof but not enclosing the other two openings; other gaskets, applied to the same face of each plate, surrounding the other two openings; the gaskets of one plate having the same location and arrangement as the gaskets

of the other plates; said plates being so assembled that the chamber-defining gasket applied to one plate encloses a pair of openings near one longitudinal edge of the exchanger while the chamber defining gasket applied to an adjacent plate encloses a pair of openings near the opposite longitudinal edge of the exchanger, and identical fluid distributing devices on the several plates, the device on each plate forming with the adjacent plate a fluid flow passage substantially progressively widening from the edge of the chamber to which the communicating openings are adjacent toward the opposite edge thereof, to thereby effect a substantially equal distribution of the fluid across the chamber in the course of its flow there-through.

4. A heat exchanger comprising a plurality of heat exchanging plates in the shape of a parallelogram and each having four flow openings, one on each corner of the plate, for conducting the 20 heat exchanging fluids, the plates consisting exclusively of identical plates each pressed in its entirety from thin sheet metal, gaskets on one face of each plate, said gaskets being identically arranged on the plates and with one gasket of 25 each plate enclosing a pair of openings at one edge of the plate and the major part of the plate surface, said last openings being the inlet and the outlet openings for one fluid, the pair of openings at the opposite edge being the inlet and 30 the outlet opening for the other fluid and being located outside the space enclosed by said gasket, a separate gasket enclosing each of the latter

10
15

openings, every second of said plates being revolved, relative to the others, 180° about an axis perpendicular to the face of the plate and passing through the center of said face.

5. A heat exchanger according to claim 4, in which each plate has a plurality of spaces consisting of deformations of the plate, the deformations being unsymmetrically positioned relative to the center line of the plate, each deformation of one plate being opposite non-deformed portions of the adjacent plates.
